UNITED STATES PATENT OFFICE

Roy A. Stone, Rockford, Ill., assignor to National Lock Co., Rockford, Ill., a corporation of Delaware

Application March 17, 1944, Serial No. 526,975

4 Claims.

(Cl. 16—166)

This invention relates to hinges of the type designed for use on cabinets or chests provided with a hollow lid, such for instance as a cedar chest or a trunk.

Chests of this character are usually placed, in order to conserve space, as near a wall as possible, but if the lid be hinged at its lower edge to the wall of the chest it will, when open, project rearwardly of the chest a distance equal to the depth of the vertical walls of the lid. This necessitates placing the chest a distance from the wall equal to the depth of the lid wall in order to enable the lid to be opened.

One of the purposes of my present invention is to provide a hinge for a chest or cabinet of the character indicated which will materially reduce the projection of the lid beyond the chest rear wall during the opening and closing movements, thus enabling the chest to be set quite close to the wall. In practice the edge of a lid mounted by my improved hinge does not project during its opening and closing movements a distance greater than the thickness of the standard quarter-round usually employed as a shoe strip along the lower edge of the baseboard, consequently the chest may be set as near the wall as the quarter-round would normally permit.

Another purpose of my invention is to provide a hinge structure which will support a tray in proximity to and movable with the lid and maintain such tray in horizontal position in all opening and closing movements of the lid.

Still another purpose of my invention is to provide a hinge structure of the character indicated which will partially support or counter-balance the lid and tray during opening and closing movements of the lid, thereby minimizing the exertion required to move the lid.

In order to facilitate an understanding of my invention, I have illustrated a preferred embodiment thereof on the accompanying drawings, referring to which:

Fig. 1 is a perspective view of a chest equipped with my improved hinge, the lid being shown in open position;

Fig. 2 is an enlarged fragmentary view of one of the hinges with the lid in closed position;

Fig. 3 is a sectional view on the line 3—3 of Fig. 2;

Fig. 4 is a view similar to Fig. 2 but with the lid in open position;

Fig. 5 is a fragmentary view looking toward the left as indicated by the line 5—5 of Fig. 4, and

Fig. 6 is a view similar to views 2 and 4 but showing the lid in partially open position.

Referring to the drawings more in detail, reference character 7 indicates generally a cedar chest which may be considered illustrative of a trunk, cabinets or the like with which my invention is designed to be employed. Such chest or cabinet comprises, as customary, a rear wall 8, a front wall 9 and end walls 11 and 12, respectively. The lid which is of the usual hollow type comprises the top 13, the rear wall 14, the front wall 15 and the end walls 16 and 17, respectively.

The hinge structure by which the lid is pivotally mounted on the body of the chest comprises a body plate 18 secured to the inner face of the end wall 12, for instance. It should be noted at this point that while two hinges, one at each end of the lid, are required in each installation, I have for illustrative purposes in all showings except Fig. 1 shown one hinge only and in the following description only one hinge will be described, it being understood that the companion hinge is similarly constructed.

The plate 18 is secured to the end wall by screws 19 and the wall is recessed as indicated at 21 (Fig. 3) to accommodate a coil tension spring 22 which is connected at one end with an ear 23 turned outwardly from plate 18, and at its other end with a boss 24 slidably in a slot 25 formed in the plate. The spring 22 being of the tractile type biases the boss 24 toward the right (Figs. 2, 4 and 6) or toward its extreme position shown in Fig. 4 wherein the lid is in fully open position.

A second plate 26, which may be designated as the lid plate, is secured by screws or otherwise to the depending end wall 17 of the lid so as to extend downwardly beyond the lower edge of said lid and beyond the meeting line of the lid and body when the lid is closed, as shown in Fig. 2. A link 27 has one end pivotally connected at 20 to the rear depending portion of the plate 26 and its other end pivotally connected at 30 to the plate 18 intermediate its ends. A second link 28 has one end pivotally connected at 29 with the forward depending portion of plate 26 and its other pivotally connected at 31 with the extreme forward end of plate 18. A third link 32 has one end pivotally connected at 33 with the link 28 intermediate its ends and its other end pivotally connected at 34 with the sliding boss 24.

A fourth link 35 has one end pivotally connected at 36 with an ear 37 fixedly mounted on the inner face of the lid top 13. The opposite end of link 35 is pivotally connected at 38 with

link 39 pivoted at 31 upon the plate 18. Link 35 extends from the upper rear corner of the tray toward the lower front corner thereof, where both links are pivoted at 38 to the angular bracket 42. The tray is detachably and removably carried by two brackets 42 and headed screws or studs 43 projecting from the end walls of the tray near their upper rear corners and adapted to seat in the notches or upwardly opening slots 40 formed in the links 35.

The supporting hinge operates substantially in the following manner. Referring first to Fig. 2, wherein the chest lid is shown in closed position, it will be observed that the tray 41 is carried in substantially horizontal position in proximity to the top of the lid, so as to be substantially closed by said top. In this position of the lid the boss 24 is in its rearmost position with the tractile spring 22 fully extended and under tension. If the front edge of the lid be now lifted from the position of Fig. 2 to that of Fig. 6, the rear edge will be supported by the hinge structure and the lower edge of rear lid wall 14 will travel forwardly so that the maximum extension of the lid rearwardly of the rear body wall 11 will be relatively slight. As illustrated in Fig. 6, the chest need be set only a short distance away from the wall 43 of the room in order to have the lid clear the wall in its opening and closing movements. In all positions of the lid the tray is maintained in substantially horizontal position, and when the lid is fully open the tray may be detached by simply lifting it from the supporting notches and brackets.

It should be noted that during the opening of the lid, the spring 22 is exerting a forward pull on the boss 24, tending through the link 32 to swing the link 28 in a clockwise direction, thereby assisting in the opening of the lid and performing a balancing function which minimizes the exertion required to move the lid. Continued upward movement of the lid will bring the parts into the position shown in Figs. 1 and 4 wherein the lid is fully opened and disposed in upright position, the rear lid wall 14 is resting upon the rear portion of the chest body and the tray 41 is in horizontal and accessible position. Upon closure of the lid, a reverse movement of all of the parts occurs until the parts resume the position as shown in Fig. 2.

The structural details illustrated and described may be varied within considerable limits without departing from the spirit of the invention, as defined in the following claims.

I claim:

1. A hinge of the character indicated, comprising a body plate adapted to be mounted upon the inner face of a chest or cabinet end wall; a lid plate adapted to be mounted upon an end wall of a lid so as to project into the chest when the lid is closed; a link pivotally connected with the rear portion of the lid plate and an intermediate portion of said body plate, a second link pivotally connected to the forward portions of said plates, a boss slidably mounted on the body plate, means for biasing said boss toward its forward position

on said plate and a third link pivotally connected to said boss and to an intermediate portion of said second link.

2. A hinge of the character indicated, comprising a body plate adapted to be mounted upon the inner face of a chest or cabinet end wall, a lid plate adapted to be mounted upon an end wall of a lid so as to project into the chest when the lid is closed; a link pivotally connected with the rear portion of the lid plate and an intermediate portion of said body plate, a second link pivotally connected to the forward portions of said plates, a boss slidably mounted on the body plate, means for biasing said boss toward its forward position on said plate, a third link pivotally connected to said boss and to an intermediate portion of said second link, a fourth link adapted to be pivotally connected to the inner face of the lid top above the body plate and to extend diagonally forwardly and downwardly across the end wall of a tray secured thereto, and a fifth link pivotally connected to the forward portions of said body plate and said fourth link, whereby said tray is maintained in horizontal position during swinging movements of said lid.

3. A hinge of the character indicated, comprising a body plate adapted to be mounted upon an end wall of a chest, a lid plate adapted to be mounted upon an end wall of the chest lid, a link pivotally connecting the rear portion of the lid plate with an intermediate portion of the body plate, a second link pivotally connecting a forward portion of the lid plate with a forward portion of the body plate, a third link pivotally connected at one end to said second mentioned link, a slidably boss connected to the other end of said third link, and a spring acting on said boss against the weight of the lid exerted through said second and third links to counterbalance said lid.

4. A hinge, comprising a body plate adapted to be attached to an end wall of a chest and provided with a slot and an ear, a boss slidably in said slot, a tractile spring connecting said boss and said ear and urging the boss toward the ear, a lid plate, a plurality of links each pivoted at one end to said lid plate and at the other end to said body plate, and a link connecting an intermediate portion of one of the aforesaid links with said boss.
